8 Claims. (Cl. 139—1)

The present invention relates to shuttleless weaving machines and more especially to the design of machines of this type with a view to facilitating the operation known as deweaving, that is to say the removal of one or a number of defective weft threads.

It is known that, in the case of certain classes of weaving machines of the continuous weft feed type, the shed closes upon the weft inserter at the moment when this latter releases the weft thread which it has just introduced. Consequently, it is not possible to reverse the motion of the loom, that is to say, to operate the loom in the direction opposite to the usual forward motion of the weaving process, since the weft inserter would in that case be presented to a shed which is either closed or not open to a sufficient extent. This impossibility complicates the deweaving operation. Furthermore, if it is desired to operate in the backward direction only the parts involved in deweaving and to stop the slay and the driving mechanism of the weft inserter (or weft inserters), mechanical complications would accordingly be encountered.

The present invention relates more especially to a device which embodies known principles and permits the possibility of carrying out a deweaving operation whenever the need arises by rotating in reverse motion both the means for actuating the healds and the mechanism for selecting and presenting the weft to the inserter, in the case in which a number of different wefts are employed in the weaving process, and by also reversing the usual direction of motion of the systems for guiding and taking-up the fabric, of the system of delivery of the warp threads should this also prove necessary, or of any other operative system, whilst the devices which actuate the slay and those which actuate the weft inserter (or inserters) rotate in the normal direction. Accordingly, the deweaving operation can readily be effected inasmuch as the weft inserter is presented to a shed which is open in the normal manner.

One known form of embodiment of a device of this type consists of a shaft which is driven from the operating mechanism of the slay and of the weft inserters by means of a coupling permitting of two directions of motion and made up of a keyed sleeve slidably mounted on said shaft and provided at each end with driving dogs designed to engage in slots formed in two gear-wheels which are mounted to rotate freely on said shaft and driven in opposite directions from the operating mechanism of the slay and weft inserters, the said shaft being fitted with a directing gear-wheel which is made fast with the sliding sleeve both for translational motion and for rotary motion whilst a manually controlled rotary sliding shaft which is parallel to the shaft referred to above is coupled to the directing gear-wheel on the one hand for translational motion with a dead range of travel and on the other hand for rotary motion at the two ends of the dead range of travel by means of a system of two gear-wheels which are rigidly fixed to the manual-control shaft and are adapted to engage selectively with the directing gear-wheel.

In this known form of embodiment, the engagement of the teeth of the claw coupling with the freely rotatable motion-reversing gear-wheels is effected by means of long keys which are adapted to slide in keyways of the shaft

2

and provide a connection between the coupling sleeve and the directing gear-wheel. Owing to the small section of the keys referred-to above, the coupling which is effected by means of said keys is endowed with inadequate strength compared with the sturdiness of the other components.

The object of the invention is to produce a device which relies on the same basic principle but which is not subject to the drawback mentioned above.

To this end, according to the invention, the sliding sleeve of the coupling which permits of two directions of motion and the directing gear-wheel now constitute one and the same part.

By virtue of this design feature which results in a very simple constructional assembly, the coupling members between said sliding sleeve and the directing gear-wheel are completely eliminated since these two components have now been combined into a single part. This feature, therefore, removes the drawbacks which previously resulted from the structure consisting of long coupling keys of relatively small section as mentioned above.

Furthermore, in the known form of embodiment, the directing wheel is driven in translational motion from the manual-control shaft by means of discs which are rigidly fixed to said shaft and which thrust back said wheel axially either in one direction or the other and are applied against a portion of the edge of said wheel which extends over a small circumferential arc.

In point of fact, the effort applied by the discs against only a small portion of the periphery of the directing gear-wheel does not assist the sliding motion of this latter along its shaft. It is for this reason that, in accordance with a further characteristic feature of the present invention, the system of transmission of motion between the manual-control shaft and the directing gear-wheel comprises at least one forked unit, the arms of which are disposed in oppositely facing relation to two substantially diametrically opposite zones of the common member which constitutes the directing gear-wheel and sliding sleeve of the two-way motion-reversing coupling.

Moreover, in the known form of embodiment, the two freely rotatable gear-wheels of the two-way motion-reversing device were bevel wheels, said bevel wheels being both in mesh with a third bevel wheel which was in turn driven by the operating mechanism of the slay and weft inserters.

Such an arrangement of bevel gears is attended by a certain number of disadvantages. In fact, such bevel gears call for a relatively complex and costly assembly of ball-bearings in order to prevent play resulting from the wear of bearing surfaces which in turn results from the oblique thrust applied by the teeth; in addition, the need to disengage the teeth when carrying out angular adjustments does not permit a simple design of axial thrust-bearing for the bevel gears.

It is for the foregoing reasons that, according to another characteristic feature of the present invention, the two free-motion gear-wheels which are driven in opposite directions from the driving mechanism of the slay and weft inserters are cylindrical spur gears.

In one particular form of embodiment, one of the said free-motion gear-wheels is continuously in mesh with a cylindrical spur wheel rigidly fixed to a primary shaft which is driven from the operating mechanism of the slay and weft inserters, whilst the other free-motion gear-wheel is continuously in mesh with an intermediate gear-wheel, said intermediate gear-wheel being also continuously in mesh with another gear-wheel which is rigidly fixed to said primary shaft.

Each of the improvements hereinabove described has a contributory function in providing a device of simpler

design which is more economical both in construction and maintenance and which provides smoother and more reliable operation.

One embodiment of the invention, as given solely by way of example, is described below and illustrated diagrammatically in the accompanying drawings, in which:

FIG. 1 is a general view of the mechanism, in which only a portion of the mechanical safety device is shown;

FIG. 2 is a perspective view of the complete mechanism, with the exception of the driving members 1 to 6 defined in FIG. 1, there being also shown the components of the safety device.

In these drawings, the reference numeral 1 designates the motor shaft of the motor (not shown) of the weaving machine. The motor drives a pinion 2 in mesh with a gear-wheel 3 which is rigidly fixed to the crankshaft 4 of the loom. The crankshaft 4 drives through the intermediary of a pair of bevel gears 6 and 7 a main shaft 8 to which are firmly secured two cylindrical spur gears 9 and 10. The spur gear 9 drives directly a first gear-wheel 11 which is mounted to rotate freely on an intermediate shaft 12. The spur gear 10 drives through the intermediary of an idler pinion 13 a second spur gear-wheel 14 which is capable of rotating freely on the shaft, in the same manner as the gear-wheel 11. The gear-wheel 14 rotates in opposite direction with respect to the gear-wheel 11; the gear ratios are so determined that the angular speeds imparted to said gear-wheels 11 and 14 either in the positive or negative direction are numerically equal to the speed of the crankshaft 4.

The shaft 12 is provided between the two seats of the gear-wheels 11 and 14 with a portion 15 of larger diameter in such manner as to ensure the spaced relationship of the two wheels 11 and 14 between the frame bearings 16 and 17. On the portion 15 of the shaft 12, there is slidably mounted a coupling member consisting of a clutch sleeve 18a which is made fast for rotation with the shaft 12 by means of a key 19 (or by means of splines). The two ends of the sleeve which form the hub of a gear-wheel 18 are each provided with a coupling element such as a dog or claw 20 and 21 respectively which is adapted to fit into a corresponding coupling element or recess 22 and 23 respectively of each hub of gear-wheels 14 and 11, in such manner as to make the shaft 12 fast for rotation with one or the other of said gear-wheels 11 and 14. The coupling unit 18-20-21 must permit the engagement of the two coupling components relatively to each other only in one angular position; therefore, in the case of a number of dogs or claws, the shape and/or the position of these latter must be designed accordingly. The shaft 12 carries a number of different driving members, namely, a pinion 24 which engages with another pinion 25, both pinions having helical gear-teeth, for the purpose of driving the shaft 26 which is at right angles to the shaft 12 and which forms part of the weft-presenting mechanism 26a. The wheels 27 and 28 are roller-chain wheels; the first of these controls the movement of the heald-driving mechanism 27b through a chain transmission which includes the wheel 27 and a further chain wheel 27a secured to a shaft 27c of this mechanism. The second wheel 28 is used to drive the warp delivering beam 28g and the cloth take-up roll 28n through transmissions which include a common portion, namely, a chain transmission between the wheel 28 and a further wheel 28a secured to a rotary shaft 28b, as well as individual portions, namely, for the warp-delivering beam 28g; a screw gear 28c carried by the shaft 28b and in mesh with a screw gear 28d carried by a shaft 28e of a mechanism 28f adapted to drive the warp beam 28g, and for the cloth take-up means 28m; a screw gear 28h carried by a shaft 28k of a mechanism 28l adapted to drive the cloth take-up roll 28m.

The engagement of the shaft 12 with either one or the other of the gear-wheels 11 and 14 by displacement of the clutch sleeve 18a can take place only in a precise angular

position of each of the wheels 11 and 14 relatively to the shaft 12, in such manner that the movement of those devices which are driven from the shaft 12 such as in particular the mechanisms for drawing the healds and for presenting the weft is carried out under the necessary conditions of concordance with the movement of the crank-shaft 4.

The displacement of the wheel 18 for the purpose of making this latter fast for rotation with one of the gear-wheels 11 or 14 and the maintenance thereof in the position which has been selected are effected by means of the following members: a control shaft 29 which is parallel to the shaft 12 and the end of which is fitted with a hand-wheel 30, said control shaft being adapted to slide and to rotate freely within bearings 31 and 32 of the frame of the motion-reversing mechanism; twin gear-wheels 33 and 34 formed on enlarged end portions of a cylindrical sleeve 35 rigidly secured to the shaft 29, said sleeve being capable of meshing with the wheel 18 through one or the other of said twin gear-wheels.

The space between the enlarged portions of sleeve 35 forms an annular groove designed to accommodate a stud 36 which is carried by a lever 37, said lever being rigidly secured to a cross-shaft 38 which is journalled in two bearings 39 and 40 of the frame; a double forked unit 41-42 (FIG. 2), also secured to the shaft 38, is so designed that the end portion of one pair of arms of said forked unit, namely either the end portions 43 or the end portions 44, come into contact with the corresponding face 30 of the gear-wheel 18 as soon as either gear-wheel 33 or gear-wheel 34 is put into mesh with the gear-wheel 18 by axial displacement of the shaft 29; if the axial displacement of the shaft is continued further, the components which are under the control of the shaft 29 and the wheel 18 are accordingly moved in unison.

There is also secured to the shaft 29 a disc 45 which can be stopped in either of two rest positions determined by notches 46 and 47 of a small bar 48 carried at the end of a lever 49, the shaft or spindle 50 of said lever (as shown in FIG. 2) being pivotally mounted in bearings (not shown) of the frame of the machine. The small bar 48 is constantly urged downwards to apply pressure against the disc 45 by the action of a spring 51 (as shown in FIG. 2) one end of which is attached to the small bar 48 and the other end of which is attached to a fixed point 52 of the frame. In addition, the lever 49 carries a small plate 53 (as shown in FIG. 2), the dimensions and position of which are such that, when the lever 49 is in the bottom position, either extremity thereof touches lightly against the face of the gear-wheel 18 on the side opposite to that extremity of the hub or sleeve 18a which is engaged with the hub of one of the gear-wheels 11 or 14, thereby preventing the uncoupling of the gear-wheel 18 with respect to either one or the other of the two gear-wheels 11 and 14. On the other hand, when the lever 49 is lifted, the small plate 53 is moved away from the axis of shaft 12 and permits the sliding motion of wheel 18 along said shaft.

In order to facilitate the disengagement and maintenance of the lever 49 in the top position thereof, the spindle 50 can be extended towards the front end of the machine and be fitted with a lever 54 (as shown in FIG. 2). The desired rotation can be imparted to said spindle 50 by means of said lever 54 and this latter can be arrested in the position of disengagement of the lever 49 by means of a spring-hook 55. It is merely necessary to thrust back the said spring-hook in order to release the lever 54 and thus permit the combined assembly which forms part of the lever 49 to fall back into position under the action of the spring 51.

The operation of the device is as follows:

It being assumed that the mechanism in accordance with the invention is driven in the usual forward direction 75 by means of the gear-wheel 11, FIGS. 1 and 2 accord-

ingly illustrate said mechanism in the position of normal weaving.

In order to change over to reverse motion either for the purpose of deweaving or searching for weft threads, the lever 49 is first lifted by rotating lever 54 until this latter is caught by the hook 55. The hand-wheel 30 is pulled towards the operator and caused to rotate slightly in order to assist the engagement of gear wheel 33 with the gear-wheel 18. The stud 36 which is pushed by the internal face of gear wheel 33 imparts a movement of rotation to the shaft 38 and to the double forked unit 41-42, the end portions 44 of which are applied against the corresponding face of gear-wheel 18 which then follows the movement of translation which is imparted to the assembly of shaft 29 by the pulling effort exerted on the hand-wheel 30 until the dog 20 of the coupling gear 18 interlocks with the recess 22 of the gear-wheel 14. If there is an angular displacement between the driving members of the two gear-wheels 14 and 18, the hand-wheel 30 is caused to rotate while maintaining the pull on this latter, and the rotation thus effected is transmitted to the gear-wheel 18 by the gear-wheel 33.

After engagement of the coupling members has taken place, the hook 55 is withdrawn, thereby releasing the lever 54 and allowing the locking device constituted by the small bar 48 and small plate 53 to return downwards; if the coupling components 20 and 22 are correctly engaged to the limit of travel, the small plate 53 begins to fall back behind the gear-wheel 18 on the side opposite to that on which said plate is shown in FIG. 2. It is then necessary to thrust back the hand-wheel in order to disengage the gear wheel 33 from the gear-wheel 18; the correct position is determined by a further downward movement of the locking device when the disc 45 passes beneath the notch 47 which fits over said disc and locks this latter in position.

The return to the usual direction of operation as for normal weaving entails the same manipulations except that the hand-wheel 30 is pushed until engagement of the coupling members has taken place and then returned by pulling so as to lock the disc 45 in position by means of the notch 46 of the small bar 48.

The user can be requested always to make sure that the small bar 48 has completely returned to the bottom position thereof. It is preferable to connect said small bar to a circuit-breaker switch which can be mounted in the control circuit of the motor or the clutch in such manner as to hold the circuit open and make it impossible to start the mechanism as long as the small bar is not in the working position.

It will be understood that any alternative forms, detail improvements and uses of equivalent means could be devised without thereby departing from the scope or the spirit of the invention.

It will be readily apparent that, instead of the twin gear wheels 33, 34 separated by the annular groove of sleeve 35 and which actuates a single gear-wheel 18, provision could be made for the reverse arrangement.

The double forked unit 41-42 can be replaced by a single fork producing action on one side only of the gear-wheel 18 close to the hub thereof, either by providing said hub with a grooved portion in which the extremities of the fork penetrate, or by causing said fork extremities to be applied on the one hand against one of the faces of the wheel 18 and, on the other hand, against an annular flange formed on said hub. It would also be possible to produce action between the same members but on one side only of the hub.

It would additionally be feasible to dispense with the cross-shaft and the components mounted thereon and to fix on the manual-control shaft a single fork, the arms of which would be fitted with substantial longitudinal play inside an annular groove of the sliding sleeve of the two-way motion-reversing coupling.

It would also be possible to effect the safety locking on the double gear by bending the small bar 48 in the op-

posite direction relatively to the lever 49 and by providing said bar with four notches, which would make it possible to dispense with the disc 45.

Similarly, the stud 36 could be extended on the other side of the lever 37 with a view to effecting the safety locking on the extension thus formed, using a small bar 48 which has been bent oppositely in this case also but provided with only two notches.

What I claim is:

1. In a shuttleless weaving machine, in combination, a main rotary shaft rotating in a predetermined direction, an intermediate rotary shaft, heald driving means and cloth take-up driving means firmly connected to said intermediate rotary shaft, a first and a second gear wheel loosely mounted some distance apart on said intermediate rotary shaft, the facing ends of said gear wheels having coupling elements, gear means operatively connecting said main shaft with said first and second gear wheels for rotating said gear wheels in opposite direction, a clutch sleeve rotatable along with said intermediate shaft and movable longitudinally relatively thereto between said first and second gear wheels, said clutch sleeve having coupling elements at each end thereof adapted in a first position to mesh with the corresponding coupling element of said first gear wheel for driving said intermediate shaft in one direction for the normal operation of the weaving machine and adapted in a second position to mesh with said second gear wheel for driving said intermediate shaft in the other direction for enabling deweaving, directing gear means rigidly carried by said clutch sleeve, a manually operable control shaft mounted parallel with said intermediate shaft for rotary and longitudinal sliding movement, further gear means firmly connected to said control shaft and adapted to mesh with said directing gear means, and mechanical connecting means between said control shaft and said clutch sleeve for moving said clutch sleeve into any one of its said two positions upon said control shaft being moved axially.

2. The weaving machine of claim 1, wherein said directing gear means are constituted by a directing gear wheel, said further gear means being comprised of twin gear wheels firmly secured to said control shaft and spaced apart by an axial distance greater than the width of said directing gear wheel, said control shaft having two rest positions wherein said twin gear wheels are located on opposite sides of said directing gear wheel, said control shaft being movable in opposite directions from any one of said two rest positions to intermediate positions in which the corresponding twin gear wheel engages said directing gear wheel, said mechanical connecting means between said control shaft and said clutch sleeve having a dead range of travel corresponding to the distance between each of said rest positions and a corresponding intermediate position.

3. The weaving machine of claim 1, wherein said mechanical connecting means between said control shaft and said clutch sleeve comprise at least one forked unit, the arms of which are disposed in oppositely facing relation to two substantially diametrically opposite zones of said directing gear means.

4. The weaving machine of claim 3, wherein said forked unit is a double fork and comprises four arms of which two are arranged in oppositely facing relation to two substantially diametrically opposite zones of one of the faces of said directing gear means whilst the two other arms of said forked unit are disposed in oppositely facing relation to two substantially diametrically opposite zones of the other face of said directing gear means.

5. The machine of claim 3, wherein said mechanical connecting means between said control shaft and said clutch sleeve comprises a pivoting cross-shaft on which is mounted said forked unit, a sleeve firmly connected to said control shaft and having an annular groove, a stud firmly secured to said cross-shaft and having one extremity located inside said annular groove formed in said sleeve which is firmly secured to said control shaft.

6. The machine of claim 5, wherein said grooved sleeve which is rigidly fixed to said control shaft serves as a hub for said further gear means firmly connected to said control shaft.

7. The machine of claim 1, wherein said first and second gear wheels which are driven in opposite directions on said intermediate shaft are spur gears.

8. The machine of claim 7, wherein said gear means operatively connecting said main shaft with said first and second spur gear wheels comprise a spur gear rigidly fixed to said main shaft and in mesh with said first spur gear wheel, a further spur gear wheel also rigidly fixed to said main shaft, and an intermediate idler spur gear simultaneously in mesh with said further spur gear and with said second spur gear wheel.
